OF LOS ANGELES, CALIFORNIA

COLON IRRIGATOR

Application filed August 12, 1930. Serial No. 474,784.

My invention relates to the medical art and more particularly to a colonic irrigating apparatus.

It has been customary in the practice of colon irrigation to supply fluid to the colon and depend upon gravity or reflex muscular action for the evacuation of this fluid. This practice is a slow, tedious, and unsanitary one, inasmuch as fecal matter and mucoid substances frequently become lodged in a protuberance in the walls of the colon and become hardened, and it is therefore desirable to provide means for forcibly drawing off this fluid in order to dislodge the foreign substances.

It is an object of my invention to provide an apparatus of the class described which includes suction providing means for quickly and efficiently carrying off, in a sanitary manner, the discharged fluids. To accomplish this I provide an insertion member connected to a fluid supply reservoir, through which I supply a solution to the colon by gravity and subsequently draw off this fluid through a discharge passage connected to the insertion member and a means creating a vacuum.

It is necessary that the extent of the suction exerted in the discharge passage be varied at intervals. This necessitates a variation in the vacuum with which the discharge passage connects in order that the syphon effect may be retarded to a desired extent.

It is an object of my invention to provide an apparatus of the class described which includes means for controlling the rate at which the fluid is drawn off from the colon through the discharge passage, and for proportionately varying the rate of flow in this passage and the degree of suction created therein by the suction providing means.

In some cases it is desirable to supply solution to the colon rapidly and at other times very slowly, and it is therefore desirable to provide control means for varying the volume of fluid provided by the supply reservoir.

It is another object of my invention to provide in an apparatus of this class, means for varying the flow of the solution from the

supply reservoir to the colon or for completely stopping this flow at intervals.

It is likewise desirable, for obvious reasons, to have facilities for the observation of the fluid passing through the discharge passage. It is therefore another object of my invention to provide in a colonic irrigating apparatus means for continuous observation of the character of the fluid passing through the discharge passage.

It is a further object of the invention to provide check means arranged in the discharge passage which permits the discharged fluid to flow from the insertion member to the suction providing means, but prevents a flow from the suction providing means toward the insertion member.

It is frequently necessary during colonic irrigation as practiced in the medical art, to stimulate the action of the voluntary and the involuntary abdominal muscles to overcome a partial paralysis of these muscles. This stimulation is accomplished by a treatment known in the art as "sinusoidal modality" or interrupted galvanic modality, these treatments being performed by a device well-known in the art, which comprises, in short, an apparatus including a pair of electric conducting pads adapted to be placed on the back and abdomen of a patient, there being conductors connecting these pads to the device which is adapted to transmit intermittent electrical impulses through the body of the patient with stimulating effect upon the above mentioned abdominal muscles.

The sinusoidal modality and the interrupted galvanic modality treatments, as known in the art, are administered by a device which is an entirely individual unit intended for use independent of other apparatus, such as colonic irrigation apparatus.

It is an object of my invention to provide a colonic irrigation apparatus including means adapted for connection to an auxiliary device for administering the sinusoidal modality or the interrupted galvanic modality treatments so that the last mentioned device is controlled by the operating mechanism of the irrigating apparatus comprising my invention.

I have discovered that the most effective time to administer these stimulating electrical impulses to inactive abdominal muscles is during the period in which suction is being applied to the colon of the patient, these impulses greatly assisting in loosening the hardened fecal matter adhering to the colon and encouraging reflex action of both the voluntary and involuntary abdominal muscles.

It is therefore another object of my invention to provide in the colonic irrigating apparatus described, means operable by the control mechanism embodied in the apparatus to close a circuit included in a device for administering the sinusoidal modality or an equivalent treatment simultaneously with the syphon effect exerted on the colon of the patient, as previously described.

It is another object of my invention to provide novel means of administering these stimulating electrical impulses to the abdominal muscles of a patient by providing a single conducting pad adapted to be applied to the abdomen of the patient, and novel means for completing an electric circuit through the body of the patient by using the fluid within the discharge passage of the apparatus and the insertion member inserted in the colon of the patient as a current conductor.

It is also an object of my invention to provide a method and apparatus whereby it is possible to treat the entire colonic tract electrically or electrochemically by use of a liquid electrode filling the colon and a movable external electrode which may be applied to the abdomen or back and which is adapted to be moved across the exterior of the abdomen or of the back so as to concentrate the electric activity at various portions of the colon. By placing the electrode on the exterior of the body adjacent one end of the colon, conducting electrical energy from one electrode to the other, and moving the exterior electrode progressively along the portions of the body lying adjacent the colon, the entire colonic tract may be electrically treated, but the electrical application, instead of being general, will be localized progressively throughout the entire extent of the colon. When chemical solutions are employed, the polarity of the electric current may be reversed.

Other objects and advantages will be made apparent in the following specification and the accompanying drawing.

Referring to the drawing:

Fig. 1 is a diagrammatic utility view illustrating a complete apparatus embodying the features of my invention.

Fig. 2 is a perspective view of the control mechanism of the device with the housing thereof broken away for simplicity of illustration.

Fig. 3 is a sectional view through the suction providing means of the invention taken as indicated by the line 3—3 of Fig. 2.

Fig. 4 is a sectional view taken on a median horizontal plane through the operating valve of the device, as indicated by the line 4—4 of Fig. 2.

Fig. 5 is a fragmentary section of an insertion member, such as is readily obtainable commercially, and which is particularly adapted for use with my invention.

In the drawing, 11 indicates a fluid supply reservoir which may be of any desired type and be arranged in any well-known manner to supply a solution at various predetermined temperatures. The numeral 12 indicates an insertion member adapted for insertion in an orifice of the body, this insertion member being connected through control mechanism generally designated by the numeral 13 to the fluid supply reservoir 11.

Referring to Fig. 2 in particular, in which the details of construction of the control mechanism are shown, I provide a housing 14 which may be of a rectangular shape having side walls 15, end walls 16, a bottom 17, and a removable cover plate 18. Extending longitudinally through the housing 14 is a tubular member generally designated by the numeral 19 in which is provided a three-way valve 20, a check valve 21 of an ordinary type, and an ejector 22. All of these members threadedly connected together by suitable lengths of tubing comprise the tubular member 19, which I will hereinafter refer to as the discharge passage. Threadedly connected to the third side of the three-way valve 20 is a laterally extending pipe 19a, which projects through the side wall 15 of the housing 14, as shown in Fig. 2, and is provided with a nipple 23 adapted to be connected to a supply pipe 24 in such a manner as to directly connect the pipe 19a to the fluid supply reservoir 11.

As shown in Fig. 2, the extreme outer ends of the tubular member 19 are formed to provide nipples 25 and 26, the nipple 25 being adapted for connection to the insertion member 12 by a suitable length of flexible tubing 27, indicated in Fig. 1, and the nipple 26 being adapted for connection with a discharge line 28 leading to a sewage system.

In Fig. 3 I show the ejector 22 as comprising a body portion 30 having a longitudinally extending primary bore 31 into each end of which a section of the tubular member 19 is threadedly connected, as previously described. Extending obliquely relative to the longitudinal axis of the primary bore 31 and in communication therewith, is a secondary bore 32 into which is threadedly inserted a water supply tube 33. As indicated in Fig. 2, the water supply tube 33 is connected to a water main 34 which extends through an opening in one of the walls 15, this supply

tube being connected in any operable manner to a pressure gauge 35 which is positioned exteriorly of the housing 14 to afford visible evidence of the pressure within the tube 33.

5 Placed in the tube 33 at a point adjacent the three-way valve 20 is a quick-throw valve 36 which may be of any well-known type.

Connected to the valve plug 40 of the three-way valve 20 is an operating lever 41 10 adapted to extend outwardly through a longitudinally extending slot 42 in one of the walls 15 of the housing 14, this lever being operable to rotate the valve plug 40 in such a manner as to cause the supply line 19a to be

15 thrown into communication with the insertion member 12, and subsequently rotated to throw the insertion member 12 into communication with the discharge line 28 for a purpose hereinafter described. Formed integrally with the lever 41 at a point adjacent the three-way valve 20 is an arm 45 adapted to be pivotally connected as by a pin and slot connection 46 to a link 47 which is secured to the gate of the quick-throw valve

20 25 36 in the water supply line 33 as indicated at 48 in Fig. 2.

The operation of my invention is as follows. With the fluid supply reservoir 11 containing a predetermined amount of solution at any desired temperature, the insertion member 12 is inserted in the colon of a patient, the operating lever 41 is then moved into the position indicated in dotted lines 50 of Figs. 2 and 4, which causes the valve gate

35 40 to assume the position shown in full lines in Fig. 4, this position allowing the solution to flow by gravity through the lateral fluid supply pipe 19a, the valve 20, and the flexible tube 27 to the insertion member 12.

40 45 If at any time in the period during which the solution is being delivered to the insertion member 12 it is desired to reduce the flow of the solution or to completely stop the flow thereof, the lever 41 may be moved into the position shown in solid lines in Fig. 2, at which time the valve gate 40 of the valve 20 will assume the position indicated by the dotted lines 51 of Fig. 4, which completely stops the flow of the solution.

50 55 After the solution has remained in the colon of the patient a desired period of time the lever 41 may be moved into the position indicated by the dotted lines 52 of Fig. 2, which causes the valve gate 40 to assume the position indicated by the dotted lines 53 in Fig. 4, throwing the insertion member 12 into communication with the discharge passage 19. It will be understood by an inspection of Fig. 2 that when the lever 41 is thrown

60 65 into the position indicated by the dotted lines 52, the arm 45 will swing in the direction indicated by the arrow 55 of Fig. 2, this movement being operable to open the quick throw valve 36, placing the water supply pipe 33 in communication with the water

main 34 and causing water to be delivered under pressure into the secondary orifice 32 in the direction of the arrow 60. It will be seen that this flow of water under pressure when delivered into the primary bore 31, as indicated by the arrow 61 in Fig. 3, will, according to a well-known principle of physics, create a vacuum in the primary bore 31 which tends to exert a suction throughout the length of the discharge passage 19 in the direction of the arrow 62, tending to draw the fluid from the colon of the patient with sufficient force to dislodge foreign substances that may have been secreted therein.

If at any time during the withdrawal of the fluid from the colon of the patient it is desired to reduce the flow or to entirely stop the flow of fluid, the lever 41 may be moved from the position indicated by the dotted lines 52 of Fig. 2 into the position shown in solid lines. The lever 41, the arm 45, and the link 47 cooperate to simultaneously actuate the quick-throw valve 36 and the three-way valve 20 to proportionately reduce the flow of fluid through the discharge passage 19 and the flow of water under pressure through the water supply tube 33 and the secondary bore 32 of the ejector 22, thereby reducing the degree of suction exerted by the ejector upon the discharge passage 19.

The insertion member 12 may be provided with a transparent portion 65, as indicated in Fig. 1, for the continuous observation of the character of the fluid which is being drawn through the discharge passage 19.

In Figs. 1 and 2 of the drawing, as is somewhat diagrammatically indicated, is a device adapted to administer the sinusoidal modality or an equivalent treatment. This device, generally designated by the numeral 70 of Fig. 1, is adapted to be operable as a subsidiary apparatus to the colonic irrigating apparatus of my invention, it being understood that the irrigating apparatus as above described may be operated independently of the apparatus 70. The apparatus 70 includes an electric conducting pad 71, preferably formed of a fibrous material such as felt, which is saturated with water, and is positioned upon the abdomen of the patient.

70 75 Connecting the pad 71 to a terminal 72 of a current interrupter 72a is a conductor 73 in which is interposed a potential source of current, indicated at 73a in Fig. 1. As shown in Fig. 2, I provide a bracket member 74 mounted within the housing 14 upon one of the walls 15 thereof, this bracket preferably being formed of an insulating material. Secured to the bracket 74 is a spring contact 75

80 85 adapted to extend into a position adjacent the end 76 of the arm 45 and in the path of travel thereof. Secured to the bracket 74 is a terminal post 77 connected to the contact 75, this post being connected to the terminal

ductor 79, this interrupter being operable to intermittently break and complete the circuit including the conductors 73 and 79.

It will be seen that in the operation of this subsidiary device the contact 75 will be engaged by the end 76 of the arm 45 when the lever 41 is thrown into the position indicated by dotted lines 52 in Fig. 2, which position, as previously described, is operable to throw 10 the insertion member 12 into communication with the discharge passage 19 of the invention. This contact causes current to be delivered from the source of current 73a through the interrupter 72a, the conductor 79, 15 the contact 75, the arm 45, and the body of the valve 20 to the fluid flowing through the discharge passage 19, this fluid acting as an electrode which cooperates with the pad 71, comprising another electrode, to deliver intermittent electrical impulses to the abdominal 20 muscles of the patient.

It is an important feature of my invention that the solution may be delivered to the colon of the patient and be allowed to remain 25 therein for any desired period and then be forcibly withdrawn therefrom without necessitating the removal of the insertion member 12.

It is another important feature of my invention that the flow of the fluid through the discharge passage 19 may be varied in direct proportion to the degree of suction created therein by the suction providing means, this being accomplished by the simultaneous operation 30 of the valves in the water supply pipes and the exhaust passage by the operating lever of the device.

It should be understood that the details of construction of the suction providing member 40 described herein are unimportant to the operation of the device, inasmuch as any well-known siphon, vacuum pump, or suction apparatus may be used satisfactorily in the operation thereof.

It should also be understood that the insertion member herein described has been shown merely for the purpose of illustration, as various types thereof are readily obtainable commercially and equally efficient for use in 50 connection with an apparatus of the type described.

It is another important feature of the invention to provide check means positioned in the discharge passage and being operable to 55 permit fluid to flow from the insertion member to the suction providing device of the invention, but to effectively prevent fluid under pressure from being forced backwardly from the suction providing device to the insertion member. This is important because if the discharge line, connecting the outlet end of the pressure providing device to the sewage, becomes inadvertently obstructed the check means provided in the 60 exhaust passage obviates the possibility of

water under pressure being forced backwardly into the colon of the patient.

It is also another important feature in the operation of my irrigating apparatus that when used in connection with the apparatus 70 for administering the sinusoidal modality or an equivalent treatment, the stimulating electrical impulses are delivered simultaneously with the suction that is applied to the colon of the patient, this combination being extremely efficient, inasmuch as the subsidiary apparatus is controlled by the operating mechanism of the irrigating apparatus at the most effective time and without the removal 75 of the insertion member from the colon of the patient.

Although the apparatus herein shown and described is fully capable of performing all the purposes primarily stated, I do not wish to be restricted thereto, as it is apparent that 80 my invention is capable of being embodied in various other forms, all of which come within the scope of the appended claims.

I claim as my invention:

1. In a colonic irrigating apparatus, the combination of: a fluid supply reservoir providing a supply passage arranged to supply a fluid under pressure; a discharge passage having a three-way valve therein, said valve connecting said supply passage to said discharge passage; an insertion member connected to said discharge passage on one side of said valve, said insertion member having a single fluid passage therein and being adapted for insertion in a colon; an ejector connected to said discharge passage on the other side of said valve, said ejector utilizing a fluid under pressure and in motion to create a suction in said discharge passage; and an operating lever for said three-way valve selectively movable between two alternate positions to close said discharge passage and open communication between said supply passage and said insertion member to allow fluid to flow from said reservoir to said colon to expand said colon by the pressure under which said fluid is delivered thereto, and to close said supply passage and open communication between said discharge passage and said insertion member to allow said suction created by said ejector to forcibly draw off said fluid from said colon through said insertion member for the purpose of suddenly contracting said colon.

2. In a colonic irrigating apparatus, the combination of: a fluid supply reservoir providing a supply passage arranged to supply a fluid under pressure; a discharge passage having a three-way valve therein, said valve connecting said supply passage to said discharge passage; an insertion member connected to said discharge passage on one side of said valve, said insertion member having a single fluid passage therein and being adapted for insertion in a colon; an ejector

- connected to said discharge passage on the other side of said valve, said ejector utilizing a fluid under pressure and in motion to create a suction in said discharge passage; an operating lever for said three-way valve selectively movable between two alternate positions to close said discharge passage and open communication between said supply passage and said insertion member to allow fluid to flow from said reservoir to said colon to expand said colon by the pressure under which said fluid is delivered thereto, and to close said supply passage and open communication between said discharge passage and said insertion member to allow said suction created by said ejector to forcibly draw off said fluid from said colon through said insertion member for the purpose of suddenly contracting said colon; and mechanism operably associated with said ejector and controlled by said lever to proportionately vary the rate of flow of said fluid in said discharge passage and the degree of suction created therein by said ejector.

3. In a colonic irrigating apparatus, the combination of: a fluid supply reservoir providing a supply passage arranged to supply a fluid under pressure; a discharge passage having a three-way valve therein, said valve connecting said supply passage to said discharge passage; an insertion member connected to said discharge passage on one side of said valve, said insertion member having a single fluid passage therein and being adapted for insertion in a colon; an ejector connected to said discharge passage on the other side of said valve, said ejector utilizing a fluid under pressure and in motion to create a suction in said discharge passage; an operating lever for said three-way valve selectively movable between two alternate positions to close said discharge passage and open communication between said supply passage and said insertion member to allow fluid to flow from said reservoir to said colon to expand said colon by the pressure under which said fluid is delivered thereto, and said lever being operable when moved to another position to close said supply passage, open communication between said insertion member and said discharge passage and open said supply tube to allow said suction created by said ejector to forcibly draw off said fluid from said colon through said insertion tube for the purpose of suddenly contracting said colon.

4. In a colonic irrigating apparatus, the combination of: a fluid supply reservoir providing a supply passage arranged to supply a fluid under pressure; a discharge passage having a three-way valve therein, said valve connecting said supply passage to said discharge passage; an insertion member connected to said discharge passage on one side of said valve, said insertion member having a single fluid passage therein and being adapted for insertion in a colon; an ejector means comprising a body providing a primary bore connected to said discharge member on the other side of said valve and a secondary bore converging with said primary bore; a fluid supply tube connected to said secondary bore and adapted to deliver a fluid under pressure convergently into said primary bore to create a suction in said discharge passage; ejector operating valve means in said fluid supply tube; and lever means associated with said three-way valve and said ejector operating valve, said lever being operable when moved to one position to simultaneously operate said valves to close said supply tube, close said discharge passage, and open communication between said supply passage and said insertion member to allow fluid to flow from said reservoir to said colon to expand said colon by the pressure under which said fluid is delivered thereto, and said lever being operable when moved to another position to close said supply passage, open communication between said insertion member and said discharge passage and open said supply tube to allow said suction created by said ejector to forcibly draw off said fluid from said colon through said insertion tube for the purpose of suddenly contracting said colon.

5. In a colonic irrigating apparatus, the combination of: a fluid supply reservoir providing a supply passage arranged to supply a fluid under pressure; a discharge passage having a three-way valve therein, said valve connecting said supply passage to said discharge passage; an insertion member connected to said discharge passage on one side of said valve, said insertion member having a single fluid passage therein and being adapted for insertion in a colon; an ejector means comprising a body providing a primary bore connected to said discharge member on the other side of said valve and a secondary bore converging with said primary bore; a fluid supply tube connected to said secondary bore and adapted to deliver a fluid under pressure convergently into said primary bore to create a suction in said discharge passage; ejector operating valve means in said fluid supply tube; lever means associated with said three-way valve and said ejector operating valve, said lever being operable when moved to one position to simultaneously operate said valves to close said supply tube, close said discharge passage and open communication between said supply passage and said insertion member to allow fluid to flow from said reservoir to said colon to expand said colon by the pressure under which said fluid is delivered thereto, and to close said supply passage and open communication between said discharge passage and said insertion member to allow said suction created by said ejector to forcibly draw off said fluid from said colon through said insertion member for the purpose of suddenly contracting said colon; mechanism operably associated with said ejector and controlled by said lever to proportionately vary the rate of flow of said fluid in said discharge passage and the degree of suction created therein by said ejector; and check means provided in said discharge passage and operable to permit fluid to flow from said insertion member through said discharge passage toward said ejector but to prevent a return flow of fluid from said discharge passage to said insertion member.

- open communication between said supply passage and said insertion member to allow fluid to flow from said reservoir to said colon to expand said colon by the pressure under 5 which said fluid is delivered thereto, and said lever being operable when moved to another position to close said supply passage, open communication between said insertion member and said discharge passage and open said 10 supply tube to allow said suction created by said ejector to forcibly draw off said fluid from said colon through said insertion tube for the purpose of suddenly contracting said colon; mechanism operably associated with 15 said ejector and controlled by said lever to proportionately vary the rate of flow of said fluid in said discharge passage and the degree of suction created therein by said ejector; and check means provided in said discharge passage and operable to permit fluid 20 to flow from said insertion member through said discharge passage toward said ejector but to prevent a return flow of fluid from said discharge passage to said insertion member. 25 6. In a colonic irrigating device of the character described, the combination of: a fluid reservoir having a delivery passage arranged to deliver a fluid; an insertion member having a single fluid passage therein 30 adapted for insertion in a colon; a discharge passage having an ejector therein adapted to create a suction in said discharge passage; valve means connecting said delivery passage, said insertion member and said discharge passage, whereby communication between said delivery passage and said insertion member, and said insertion member and said discharge member is alternately established for the purpose of alternately delivering 35 fluid under pressure to the colon to expand said colon and forcibly withdrawing said fluid from said colon by suction created by said ejector to suddenly contract said colon. 40 7. In a colonic irrigating device of the character described, the combination of: a fluid reservoir having a delivery passage arranged to deliver a fluid; an insertion member having a single fluid passage therein 45 adapted for insertion in a colon; a discharge passage arranged to mechanically provide a suction therein and being connected to said fluid delivery passage and said insertion member; and means for alternately establishing open communication between said delivery passage and said insertion member, and between said insertion member and said discharge passage for the purpose of alternately delivering fluid to said colon to expand said colon and forcibly withdrawing said fluid from said colon by suction to suddenly contract said colon. 50 8. In a colon exercising device for rehabili- 115 tating normal peristalsis of the colon, the combination of: an insertion tube adapted to be inserted into the rectal portion of the colon; means for delivering liquid to said colon through said insertion tube to fill said colon and under sufficient pressure to expand said colon; and means for withdrawing said liquid from said colon through said insertion tube and for producing in said colon sufficient vacuum to contract same. 9. In a colon exercising device for rehabili- 120 tating normal peristalsis of the colon, the combination of: an insertion tube adapted to be inserted into the rectal portion of the colon; and means for alternately supplying liquid to said colon through said insertion tube and removing said liquid in such a manner as to alternately expand and contract said colon to rehabilitate peristalsis. In testimony whereof, I have hereunto set my hand at Los Angeles, California, this 8th day of August, 1930. HUGH E. DIERKER.
